UNITED STATES PATENT OFFICE.

ANGELO GABRIELE CICERCHI, OF HILLSVILLE, PENNSYLVANIA.

EARRING.

1,419,021.

Specification of Letters Patent. Patented June 6, 1922.

Application filed October 10, 1921. Serial No. 506,923.

To all whom it may concern:

Be it known that I, ANGELO G. CICERCHI, a citizen of the United States, residing at Hillsboro, in the county of Lawrence and 5 State of Pennsylvania, have invented new and useful Improvements in Earrings, and of which the following is a specification.

This invention relates to jewelry, particularly to ear rings, and has for its object the 10 provision of a novel ear ring construction in which either the screw which passes through a hole in the lobe of the ear or the nut which is threaded upon the screw is swiveled with respect to the body of the 15 device whereby to prevent loss of either the screw or the nut and consequent loss of the ear ring.

It is well known that in the ordinary types 20 of ear rings in which a screw is provided for holding the device in place upon the lobe of the ear, it frequently occurs that the screw becomes loosened and may then drop out which will of course result in the probable loss of the entire ear ring. It is with 25 this objection in view that the present invention has been designed.

An important object of the invention is the formation of the ear ring proper in hingedly connection sections, one of which 30 carries the clamping screw and the other of which either carries or is formed with the nut associated with the screw.

An additional object is the provision of a structure of this character which will be 35 simple and inexpensive in manufacture, easy to apply and adjust, efficient in use, positive in its holding action, durable, and a general improvement in the art.

With the above and other objects and advantages in view, the invention consists in the details of construction to be hereinafter more fully described and claimed, and illustrated in the accompanying drawing, in which,

45 Figure 1 is a perspective view of an ear ring constructed in accordance with my invention and showing the same in open position.

Figure 2 is a longitudinal sectional view 50 therethrough showing the parts in closed position.

Figure 3 is a perspective view of a modified form and,

55 Figure 4 is a longitudinal sectional view therethrough.

Referring more particularly to the draw-

ings and especially to the form shown in Figures 1 and 2 the numeral 10 designates the U shaped body of the ear ring which includes a long arm 11 which is provided at 60 its free end with a slot 12, and also which includes a short arm 13 upon the free end of which is hinged as shown at 14, the ear ring section or member 15 which constitutes the ornament or which may be formed as 65 a setting for any jewel or the like. Opposite the slot 12 in the long arm 11, the section or member 15 is provided with a threaded hole 16, within which is engaged the threaded end of a screw 17 which is carried permanently by the long arm 11 and which passes through the slot 12 therein. Inwardly of the arm 11 the screw 17 is formed with an enlarged flange 18 and outwardly of the arm the screw is provided with a 75 relatively large head 19 by means of which it may be turned. Owing to the fact that the slotted end of the long arm 11 is disposed between the flange and the head 19 it will be apparent that the screw is permanently swiveled upon the long arm of the 80 frame or body of the device.

In applying this type of the device to the ear it will be apparent that the screw 17 is passed through the usual hole formed in the 85 lobe of the ear, the lobe of the ear being received between the arms of the U-shaped body 10. The hingedly mounted section or member 15 is then swung so that the hole 16 therein will be opposite the point of the 90 screw 17 after which the operator grasps the head 19 of the screw and turns the same so as to screw it into the threaded hole 16. When the device is thus applied it will be readily apparent that it will be held firmly 95 associated with the ear. If it should by any chance occur that the screw 17 becomes unscrewed it is still hardly likely that the ear ring would be lost owing to the fact that the screw still will be extending through 100 the hole in the lobe of the ear and thus prevent the device from dropping off.

Referring more particularly to Figures 3 and 4 of the drawings, I have shown the device as comprising a substantially U-shaped 105 body 20 upon the shorter arm of which is hingedly mounted as shown at 21, the ornament or section 22 of the ear ring which may be formed as a setting for a stone or the like. The longer arm of the body 20 is threaded as shown. Rigidly secured to 110 or hingedly connected with the hinged sec-

tion 22 is an arm 23 which has its free end formed with an elongated slot 24 through which the threaded end of the body 20 is designed to be passed. Swivelly connected 5 within this slot 24 is a nut member 25 which may be made more or less ornamental as preferred and this nut member is of course permanently associated with the arm 23.

In applying this form of the device to the 10 ear, the threaded end of the body 20 is inserted through the hole in the lobe of the ear in the usual manner after which the arm 23 is so swung as to bring the nut member 25 carried thereby in such position to be 15 screwed onto the threaded end of the body 20. When the device is thus installed in position it will be readily apparent that displacement of the parts will be prevented and that even in the event that the nut 25 becomes 20 unscrewed the device still will not drop from the ear as the body 20 would still be engaged through the hole in the lobe.

From the foregoing description and a study 25 of the drawings it will be readily apparent that I have thus provided an extremely simple and consequently inexpensive ear ring construction which will be very secure inasmuch as there is a very positive holding action at all times, the construction being furthermore such that in the event of loosening 30 of the screw devices which hold the ear ring in place loss will be prevented owing to the fact that there will still be a member engaged through the hole in the lobe.

35 While I have shown and described the

preferred embodiment of the invention, it is of course to be understood that I reserve the right to make such changes in the form, construction and arrangement of parts as will not depart from the spirit of the invention or the scope of the subjoined claims.

Having thus described my invention I claim;

1. An ear ring comprising a substantially U-shaped body having arms of unequal length, a member hingedly mounted upon the free end of the shorter arm, said hinged section being adapted to support an ornament, said hinged section being provided with a threaded hole, the free ends of the longer arm of the body being formed with an elongated slot, and a screw extending through and permanently swivelly associated with said slot and adapted to be threaded into said hole.

2. An ear ring comprising a substantially U-shape body member having arms of unequal length, a section pivotally mounted upon the free end of the shorter arm and adapted to support an ornament, the longer arm of said U-shaped body being threaded, an arm connected with said pivoted section and formed with an elongated slot, and a nut member permanently swivelly associated with said arm within said slot and adapted for threaded engagement upon the threaded end of the U-shaped member.

In testimony whereof I affix my signature.

ANGELO GABRIELE CICERCHI.
